UNITED STATES PATENT OFFICE.

RUDOLPH RAMSEK, OF ST. LOUIS, MISSOURI, ASSIGNOR TO ANNA RAMSEK, OF ST. LOUIS, MISSOURI.

COMBINED LAUNDRY GAS-STOVE AND WASHING-MACHINE BOILER.

1,103,313.

Specification of Letters Patent.

Patented July 14, 1914.

Application filed December 20, 1912. Serial No. 737,834.

To all whom it may concern:

Be it known that I, RUDOLPH RAMSEK, a citizen of the United States, and resident of St. Louis, Missouri, have invented a certain 5 new and useful Improvement in Combined Laundry Gas-Stoves and Washing-Machine Boilers, of which the following is a specification containing a full, clear, and exact description, reference being had to the accompanying drawings, forming a part hereof.

My invention relates to an improvement in washing machine boilers, and consists in the novel construction hereinafter described 15 and specifically designated in the appended claim.

The object of my invention is to provide an improved gas heating attachment for washing machine boilers, wherein the water necessary for the laundry work may be heated within the washing machine boiler itself.

In the drawings Figure 1 is a sectional side elevation of a washing machine boiler 25 having my invention applied thereto; Fig. 2 is a sectional top plan view of the same; Fig. 3 is a front elevation of the upper portion of the washing machine boiler, the lower portion being broken away.

The numeral 1 indicates the body of the washing machine boiler, which may be square in form as shown, or may be circular or of any other desired shape. The top of the boiler is normally closed by means of a 35 cover 2 secured to the boiler by the hinges 3. The vertical sides of the boiler 1 are preferably made of corrugated metal as shown.

Mounted as usual in the hinged cover 2 is the ordinary washing machine rubber 4 for the purpose of agitating the clothes 40 within the boiler. Said rubber 4 is provided with braces 5, and its shaft 6 projects upwardly beyond the cover so that motion may be imparted thereto by means of a 45 common handle (not shown), or a motor-connection therewith.

A series of vertical round rubbing bars 7 are located in each corner of the boiler 1, with their lower ends soldered or otherwise 50 secured to the bottom of the boiler, while their upper ends are soldered or otherwise secured to the upper end of a plate 8 which is fixed in each corner of the boiler, above the upper ends of said rods beneath said 55 cover 2.

The boiler 1 is mounted upon a burner-casing 9 in which is mounted a common gas-burner 10 supplied with gas and air through a flexible tube or other common connection 11 controlled by a valve 12 located upon the exterior of said casing. 60

The numeral 13 indicates a common support for the gas-burner.

The burner-casing 9 is provided with a door-opening 14 for affording access to the 65 burner 10, and said opening is normally closed by a common hinged door 15.

The burner-casing 9 is supported by a series of legs 16, the upper ends of which are in the form of horizontal arms extending beneath and secured to the bottom of the casing by means of rivets or bolts 17 passing through lateral flanges on said horizontal arms and through apertures in the bottom of said casing. Binding and bracing strips 18 extend continuously across a considerable portion of the vertical body of the legs 16 upwardly at each corner of the burner-casing 9, completely across the latter and across the boiler 1, and said strips are 70 secured to lateral flanges on said legs by means of bolts or rivets 19, and are secured by solder throughout the remainder of their length to the said burner-casing and to the boiler, thereby securely tying together the 75 three structures above named.

The numeral 20 indicates an outlet-pipe applied to the upper portion of the burner-casing 9, for carrying therefrom the products of combustion. 80

The numeral 21 indicates a common faucet by means of which the soiled water may be discharged from the said boiler 1. Said faucet 21 is preferably provided with a hose-connection 22, whereby a common hose may 95 be applied thereto for the purpose of connecting said faucet with a water supply to be used in filling the boiler with fresh water when desired.

The numeral 25 indicates a pair of common arms which extend at an angle upwardly and outwardly from the side of said wash-boiler proper 1, to support a washboard or any other desired article; the lower ends of said arms being secured to said boiler 100 by means of suitable rivets. 105

The operation of my invention will be readily apparent without further description.

The said horizontal bottom-supporting- 110

arms of the said legs 16 act very efficiently to support the flexible sheet metal bottom of the said burner-containing casing 9, and without said supporting-arms the said bottom would bulge downwardly. Furthermore, the said bottom-supporting-arms act as braces for the said legs 16.

1 claim:

The improved combined laundry gas-stove and washing machine boiler, comprising a sheet-metal wash boiler proper, a separate sheet-metal burner-containing-casing beneath said boiler, a series of separate supporting legs each having a horizontal flanged bottom-supporting arm extending a distance beneath and in contact with the bottom of said casing, and each leg also having verti-

cal flanges, a series of binding and bracing strips extending continuously alongside of a considerable portion of the vertical flanges 20 of the said legs upwardly completely across said burner-casing to and across the said boiler and overlapping the said casing and the said boiler, and suitable means for fixing said series of strips to said vertical leg-flanges, casing and boiler. 25

In testimony whereof, I have signed my name to this specification, in presence of two subscribing witnesses.

RUDOLPH RAMSEK.
